CLAIM

The ornamental design for a lid for water bottle, as shown and described.

DESCRIPTION

FIG. 1 is a front, top and left side perspective view of a lid for water bottle showing my new design;

FIG. 2 is a rear, bottom and left side perspective view thereof;

FIG. 3 is a front and left side view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a cross-sectional view taken along line **10-10** of FIG. 9.

The broken lines in the drawings illustrate portions of the lid for water bottle which form no part of the claimed design.
